UNITED STATES PATENT OFFICE.

SAMUEL KORN, OF CINCINNATI, OHIO.

POWDER CAN.

Application filed April 18, 1922. Serial No. 554,532.

The objects of my invention are to provide a simple, convenient, efficient and economical can that will discharge tooth powder onto a tooth brush without spilling or wasting the powder.

My invention consists in the parts and combination and arrangement of parts and in the details of construction as herein set forth and claimed.

10 My invention relates to improvements in powder cans and more particularly to cans used for tooth powder.

In the drawing:

15 Fig. 1 is an isometric view of my novel powder can;

Fig. 2 is a plan view thereof;

Fig. 3 is a longitudinal section taken on the line 3—3 of Fig. 2;

20 Fig. 4 is a side elevation of my novel tooth powder can shown in operative position and the toothbrush thereunder showing its relation to the can;

Fig. 5 is a transverse section taken on the line 5—5 of Fig. 3;

25 Fig. 6 is a perspective view of the slide;

Fig. 7 is a perspective view of the slide mounting;

Fig. 8 is a side elevation of the slide;

30 Fig. 9 is a perspective view of a portion of the slide showing the method of assembling same;

Fig. 10 is a plan view of the top cap of the can; and

35 Fig. 11 is an elevational view of the can showing the discharge slot.

In the embodiment of my invention as illustrated and which shows a preferred construction the can comprises a cylindrical tapered casing 1 having its small end at the 40 top and having caps 2 and 3 clamped thereon which close the ends of the can. Cap 2 has an irregular slot 4 therein for the purpose of slidably receiving slide 5. Slide 5 consists of two members 6 and 7 rigidly held 45 together by ears 8 and 9 on member 7 and engaging extensions 10 and 11 of member 6.

The sides 12 and 13 are slidably supported in grooves 14 and 15 of U-shaped slide mounting 16. U-shaped slide mounting 16 50 has an oblong slot 17 in its lower part which corresponds to oblong slot 18 in can. Said U-shaped slide mounting 16 has downwardly extending flanges 19 adapted to extend through oblong slot 18 of the can and be bent or clamped at 20 and 21 around the walls of said slot as shown in Fig. 5. The

U-shaped slide mounting 16 is preferably placed towards the top of the can so that when slide 5 is pushed within the can, apron 22 of member 7 closes oblong slot 18 of the can. When slide 5 is pushed within the can apron 22 of member 7 slides over oblong slot 18 thereby closing said oblong slot. This permits the powder within the can to drop through the oblong opening 23 of member 6 upon apron 22 of member 7 and is held upon said apron by downwardly extending flanges 28 forming part of member 6.

Slide 5 is provided with a downwardly extending flange 5' adapted to push any clinging powder toward the oblong slot whereby it is more readily discharged.

When it is desired to discharge tooth powder onto a brush, the brush is held directly under oblong slot 18 of the can and slide 5 is pulled out as shown in Fig. 4. By pulling slide 5 out until flange 24 rests or abuts against end 25 of U-shaped slide mounting 16 the apron 22 is drawn from over oblong slot 18 of the can thereby permitting the powder to drop therethrough upon brush 26. When slide 5 is pulled out the extended apron 27 of member 6 prevents or stops any more powder from dropping through slot 18.

The can is preferably tapered so as to make it easy to hold the can and the brush with one hand, thereby leaving the other hand free to operate the slide. The slide 5 is constructed so as to permit only the required amount of powder to drop through slot 18 of the can, thus preventing overloading the brush and avoiding any waste of powder.

It will thus be seen that I provide an exceedingly simple, inexpensive and efficient means for discharging tooth powder upon the brush and one which will accomplish all of the objects hereinbefore set forth.

What I claim as new and desire to secure by Letters Patent is:

1. A powder can having a slot in one side and a slot in one end, a slide mounting in said can having a slot therein adapted to register with the slot in the casing or can and a slide inserted in the slot in the cap and in the slide mounting and having an apron adapted to extend over said slots in the can when closed and having an extended apron adapted to extend over the slots in the casing and mounting when in powder discharging position.

2. In a powder can, a casing having a slot through the side near one end and having an irregular slot in one end, a slide mounting in said can mounted under said slot and having a slot adapted to register with said first named slot, a slide inserted in said irregular opening and having a slot therein adapted to register with said slots in the side of the can and in the mounting, respectively, and having a stop at each end adapted to limit its longitudinal movement and a downwardly extending flange at the inner end of the slot and a slide to brush any clinging powder and an extending apron, substantially as set forth.

3. In a powder can, a casing having a slot

in the side thereof, a slide, a longitudinal member having a slot therein adapted to register with said slot in said casing and having side walls having a guide way there-
in for receiving said slide.

4. A powder can having a slot in one side and a slot in one end, a slide mounting in said can having a slot therein adapted to register with the slot in the casing or can and a slide inserted in the slot in the cap and in the slide mounting and having an apron adapted to extend over said slots in the can when closed, substantially as set forth and for the purposes specified.

SAMUEL KORN.
